H. F. BLACKWELL,
DRILLING DEVICE,
APPLICATION FILED FEB. 18, 1920.

1,350,059.

Patented Aug. 17, 1920.

UNITED STATES PATENT OFFICE.

HENRY F. BLACKWELL, OF NEW YORK, N. Y., ASSIGNOR OF ONE-HALF TO WILLIAM H. STRAWN AND ONE-HALF TO MAUDE A. BLACKWELL, BOTH OF NEW YORK, N. Y.

DRILLING DEVICE.

1,350,059.

Specification of Letters Patent. Patented Aug. 17, 1920.

Application filed February 18, 1920. Serial No. 359,586.

To all whom it may concern:

Be it known that I, HENRY F. BLACKWELL, a citizen of the United States, and a resident of the city, county, and State of New York, have invented a certain new and useful Improvement in Drilling Devices, of which the following is a specification.

This invention relates to a drilling or rock boring device, and an object of the invention is to provide a rotary drilling device or apparatus in which the drilling or cutting member of the device is driven by a motor or other source of power which is so arranged that it forms a part of the device itself. In other words, the cutting member and its power means is in the form of a complete and self-contained unit.

A further object of this invention is to provide a drilling device of the character above mentioned in which the borings, cuttings or "spoil" displaced by the drilling action are comminuted or pulverized and forced or removed upward to the surface of the earth so that the progress of the drill in its digging operation is not interfered with, and also so that the progress of the drilling operation can be ascertained by examining the "cuttings" or "spoil" at any time without the necessity for removing the drilling device from the hole or excavation in which it is operating. A further object of this invention is to provide a drilling device which will automatically remove the cuttings or spoil from the hole or excavation which it is producing, thereby obviating the necessity for constantly removing the drill from its excavation for the purpose of bucketing out or clearing the excavation.

With these objects and other objects which may hereinafter appear, I have devised the particular arrangement of parts hereinafter set forth, and more particularly pointed out in the claims appended hereto.

In the drawings forming a part hereof, Figure 1 is a vertical sectional elevation of the drilling device;

Fig. 2 is a sectional view on the line 2—2 of Fig. 1, looking in the direction of the arrows;

Fig. 3 is a vertical sectional view of one of the drill-casing rollers and the mounting therefor;

Fig. 4 is a vertical sectional view of the cutting head; and

Fig. 5 is a view of the under face of the cutting head.

Throughout the various views of the drawings, similar reference characters designate similar parts.

In the preferred embodiment of my invention, as illustrated in the accompanying drawing, 1 indicates the casing of the device which is preferably in the form of an elongated tubular member. Mounted within the casing, and intermediate the upper and lower ends of the same, is the power means of the drill comprising a motor 2, which is preferably of a form that its frame 3 fits snugly within the casing 1. The motor may be of any special or conventional form and is preferably a small alternate current electric motor of the squirrel cage, rotating-field type, of two or three phases. This type of motor is believed to be very suitably adapted to perform the work for which it is intended in this instance.

The motor is provided with the usual field-winding stator 4, and rotor 5. The rotor 5 is preferably tubular or hollow, and fixed to and extending through the same is a hollow shaft 6. This shaft 6 projects above and below the frame 3 of the motor and passes through the water tight washers or glands 7, which are secured within the casing above and below the motor to prevent moisture from obtaining access to the same. Secured to the lower end of the tubular shaft 6 is a laterally extending, flanged member or spider 8, which is provided with a pair of downwardly projecting pins 9, which are placed diametrically opposite one another, and upon each one of these pins is rotatably mounted a pinion gear 10. The ends of the pins 9 are connected by a washer or plate 11 to hold these pins at constant distances and to hold the pinions 10 in place. The pinions 10 mesh with an internal or ring gear 12, which is in the nature of an annular rack and which is fixed to the wall of the casing and thus held stationary while the device is in operation. These pinions 10 also mesh with an internal gear 13 which is secured upon the end of a hollow or tubular shaft 14 extending vertically through the

casing 1 below the motor. The hollow shaft 14 is mounted to rotate in a bearing 15, secured within the casing, and this bearing 15 is provided with shoulders 16 which support and act as a bearing for the downwardly-extending end of the internal gear 13. Mounted upon and secured to the tubular shaft 14 is a supporting plate or thrust collar 17 which forms a shoulder or support for a thrust bearing 18. The thrust bearing 18 is thus interposed between the supporting member 17 and the lower end of the bearing 15. The lower end of the casing 1 is closed by means of a gland or stuffing box 19 which forms a bearing for the tubular shaft 14 adjacent its end, and said tubular shaft 14 rotates therein and has its lower end projecting beneath the end of the tubular casing 1. Threaded upon the projecting end of the tubular shaft 14 is the cutting or drill head 20. This cutting head 20 is in the nature of a conical member, and is provided with a central bore 21, which is provided for a portion of its depth with screw threads 22^a, which permit the head to thread upon engaging screw threads on the tubular shaft 14. The cutting head 20 is provided with a plurality of rotary toothed cutters 22, which are in the nature of star-wheels and are rotatably mounted upon pins 23 in the head. The rotary cutting members 22 are preferably placed in staggered alignment as indicated in Fig. 5, and are mounted in the sides of the cutting head as well as in the under face of the same as shown.

The preferred arrangement of these cutting members 22 is disclosed in Figs. 4 and 5, although the same may be modified to accord with the different forms of cutting heads that are readily applicable for use in connection with my improved drilling device.

The internal gears 12 and 13, together with the pinions 10, comprise a reduction gearing which drives the tubular shaft 14, with its attached cutting head 20, at a much lower speed than the speed of the motor 2 in a manner which will now be described.

The internal gear or rack 12 is, as heretofore mentioned, stationary or fixed to the casing 1 of the device, while the internal gear 13 is secured to and rotates with the tubular shaft 14. The rotatable internal gear 13 is provided with two teeth more than the fixed gear 12 so that at each revolution of the flanged plate member or spider 8 the internal gear 13 will be advanced two teeth. Assuming that the motor is revolving at 1200 revolutions per minute and this internal gear 13 is advanced two teeth per revolution or 2400 teeth per minute, and assuming that the gear 13 has 68 teeth, and the fixed gear 12 has 66 teeth, the gear 13 will thus be rotated 36 revolutions per

minute, consequently driving the cutting head 20 at this speed. The above is merely one illustration of the manner in which the reduction gearing can be arranged, and it will be understood that many arrangements are applicable to obtain different speeds of the cutting head 20. The flange plate member or spider 8 may also be provided with as many pinions 10 as desired, and to secure proper results, the internal gear 13 should be provided with an amount of teeth more than the teeth on the fixed internal gear 12 as there are pinions.

Through the medium of the above mentioned reduction gearing, it will be seen that the cutting head 20 is driven at a reduced speed from the motor at all times.

As before mentioned, the shaft 14 is tubular and the shaft 6 is likewise tubular, and both the shafts 6 and 14 are in vertical alignment. Extending through these shafts 6 and 14 is a continuous suction tube 24 which passes through the motor 2 and projects downwardly into the bore 21 of the cutting head 20. To prevent leakage the tube 24 is provided with suitable packing 25 at spaced apart or separated points as it extends through the tubular shafts 6 and 14.

Mounted on the end of the tubular shaft 6 above the motor is a centrifugal suction pump 26 which is preferably of the three stage form, that is, it is provided with three sets of impelling vanes 27, placed one set above the other. While three sets of superimposed vanes 27 may be preferably used, additional sets or fewer sets may be utilized to produce the requisite suction, or the form of the pump may be modified as required. The suction tube 24 is provided with discharge openings 25^a, and the tubular shaft 6 is provided with corresponding openings, so that the pump 26 can exhaust or exert suction through the tube 24.

From the foregoing, the operation of my improved drilling device will be readily understood. The motor is connected to wires 28 which extend through the upper plate 29 of the casing, and pass through a suitable conduit 30 which projects through the plate 29 as disclosed in Fig. 1, and these wires extend to any suitable source of power to operate the motor 2. The operation of the motor causes a rotation of the cutter head 1 at a reduced speed due to the reduction gearing heretofore described, and the digging operation begins. The rotary toothed cutting members 22 pulverize or comminute the "cutting" or "spoil" into such small particles that it, together with water or other liquid matter that the pump may contact with during the digging operation, is drawn by the suction of the pump through the bore 21 of the cutting head 20 up through the tube 24 and into the first set of impelling vanes 27.

of the centrifugal suction-pump. The first set of vanes 27 passes the material thus drawn upward to the second set of vanes and finally to the third set and so on. This 5 "cutting" or "spoil" is passed through the discharge opening 31 of the pump. The discharge opening 31 may be connected to a hose of suitable length so that the hose extends up to the surface of the earth, and per-
10 sons at that point may keep continual watch on the material that is being displaced by the drilling device and exhausted therefrom. By this arrangement, the progress of the drill may be constantly noted without the
15 necessity for causing it to cease its opera-
tion.

The casing 1 is provided with a plurality of openings which may serve as hand-holes or inspection openings and in each of these 20 openings is secured a cup 32 provided with a circumferential flange 33 which secures the cup to the casing 1 by means of screws 34. A gasket or washer 35 is preferably placed intermediate the circumferential flange 33
25 and the face of the casing to prevent the entrance of water and to prevent leakage of lubricating oil which may be placed within the casing to properly lubricate the mechanism contained therein.

30 Contained within the cup 32 is a coil spring 35 which bears against and tends to force outward a plate 36 in which is mounted a roller 37, the plate being provided with bearings 38 to receive the axle 39 of the
35 roller and allow free rotation of the same. Secured over the circumferential flange 33 of the cup 32 is a plate 40, which is provided with a rectangular opening or slot 41 through which the roller 37 may project.
40 The slot 41 through which the roller 37 projects holds the roller in such a position that its plane is always parallel with the axis of the drilling device. The opening 41 in the plate 40 is smaller in diameter than the
45 bearing plate 36, and thus it acts as a stop or abutment for the same, and limits the outward movement of the roller 37. Each of these rollers is thus resiliently mounted, and as they have their planes parallel with
50 the axis of the drilling device they are only rotatable in the direction that the drilling device is operating. These rollers 37, by reason of their construction, thus resiliently bear against the walls of the excavation pro-
55 duced by the drilling device, and as they are only rotatable in the direction of the movement of the device, they prevent rotation of the casing 1 within its excavation, and provide the reaction against which the cutter

60 head may work. The thrust bearing 18 permits free rotation of the tubular shaft 14, and supports the weight of the device together with the weight of the tackle, ropes or other means by which the drilling device

is suspended, and any extra weights which 65 may be needed to force the cutting head against its work. The drilling device is preferably provided with an eye 42 at each side of the casing at the upper end thereof for engagement by the right hand and left hand laid ropes or other tackle to prevent turning or twisting when the drilling device is to be lowered and removed from the ex-
70 cavation which it produces.

From the foregoing, it is obvious that my 75 invention is not to be restricted to the exact embodiment shown, but is broad enough to cover all structures coming within the scope of the annexed claims.

Having described my invention, what I 80 claim is:

1. A device of the class described, comprising a casing, power means within said casing, said power means having a shaft, a cutting head shaft driven from the power 85 shaft, a passage through both of said shafts through which comminuted material, displaced by the drilling operation, passes and suction exerting means driven by the power means for causing the comminuted material 90 to be drawn through said passage.

2. A device of the class described, comprising a casing, a motor within said casing, a shaft driven from said motor, a cutting head on said shaft, a continuous suction 95 passage extending through the cutting head, the shaft and the motor and a suction pump driven by said motor.

3. A device of the class described comprising a casing, a motor contained within said casing, a cutting head below the end of the casing driven by said motor, a suction pump within the casing and driven by the motor and a suction tube extending through the casing and into the cutting head. 100

4. A device of the class described having a casing, a motor within the same, drilling mechanism driven by the motor, a suction tube extending through the casing and drilling means, and a suction pump within the 110 casing and driven by the motor.

5. A device of the class described having a casing having a plurality of openings in its side walls, removable cups in said openings, springs in said cups, bearings adapted to be thrust outwardly by said springs, rollers mounted in said bearings and stops for limiting outward movement of said bearings. 115

6. A device of the class described, comprising a casing having an opening in its side wall, a cup mounted in said opening, a bearing within said cup, a roller mounted in said bearing, a spring within said cup forming a resilient mounting for said 120 bearing and means for restricting outward movement of said bearing.

7. A device of the class described, com-

- prising a tubular casing, a shaft and driving means for said shaft within the casing, a suction tube extending through said shaft, means for exerting suction through said suction tube a cutting head and means for driving said cutting head at a lower speed than the speed of the driving means within the casing.
8. A device of the class described, comprising a casing, a motor mounted within said casing, a tubular shaft driven by said motor, a tubular shaft driven at a reduced speed by the motor driven shaft, a cutting head driven by the last mentioned shaft, a suction tube extending through said shafts and through the cutting head, and means for exerting suction through said suction tube.
9. A device of the class described, comprising a casing, a shaft within the same, power means for driving said shaft, a suction pump driven by one end of said shaft, speed reducing means on the other end of said shaft, a cutter head, a shaft upon which said head is mounted, said cutter head shaft being driven by said speed reduction means, a suction tube extending through both of said shafts and connected to the suction pump.
10. A device of the class described, comprising a casing, a hollow shaft within the same, means within said casing for rotating said hollow shaft, a cutting head on the end of said hollow shaft, a suction tube extending through said shaft and means for exerting suction through said tube.
11. A device of the class described, comprising a tubular casing, a hollow shaft rotatably mounted within the same, power means contained within said casing for rotating said hollow shaft, a cutting head secured on the end of said hollow shaft, a plurality of cutting members rotatably mounted on said cutting head, a suction tube extending through said hollow shaft, a pump for exerting suction through said tube and means for driving said pump.
12. A device of the class described, comprising a tubular casing, a hollow shaft rotatably mounted within the same, a motor contained within the casing, means for rotating the hollow shaft at a lower speed than the speed of the motor, a conical cutting head secured to one end of said hollow shaft, a suction tube extending through said hollow shaft, and a motor-driven suction pump connected to said suction tube.
13. A device of the class described, comprising an elongated tubular casing, a motor mounted within said casing, a shaft driven by said motor, a suction pump driven by one end of said shaft, a laterally extending member on the other end of said shaft, said laterally extending member having a plurality of projections, a pinion rotatably mounted on each of said projections, an internal gear with which said pinions mesh, a shaft secured to said gear, and a cutting head attached to the end of said shaft.
14. A device of the class described, comprising a casing, a motor mounted within the same, a motor driven shaft, a suction pump driven by said shaft, a lateral member on one end of said shaft, pinions rotatably mounted on said member, a gear engaged by said pinions and rotated by the same, a shaft on which said gear is fixed and a cutting head attached to the end of said shaft.
15. A device of the class described, comprising a casing, a motor mounted within said casing, said motor having a hollow shaft, another hollow shaft driven by said motor, a cutting head on said last mentioned shaft, a suction tube extending through both of the shafts and the cutting head and means for exerting suction through said tube.
16. A device of the class described, comprising a tubular casing, a motor mounted within the same, said motor having a hollow shaft, a suction pump driven by one end of said motor shaft, a lateral projection on the opposite end of said motor shaft, pinions rotatably mounted upon said lateral projection, an annular rack secured within the casing, and adapted to mesh with said pinions, an internal gear adapted to mesh with said pinions and be rotated thereby, said gear having a greater number of teeth than the annular rack, a shaft secured to said gear, and a cutting head secured to said shaft.
17. In a device of the class described, a casing, an electric motor mounted within the same, said motor having a hollow shaft, another hollow shaft rotatably mounted within the casing, speed reduction means between the said hollow shafts so that the last mentioned hollow shaft is driven at a reduced speed, a cutting head on the last mentioned hollow shaft having a plurality of rotatably mounted cutters, a suction tube extending through both of the hollow shafts and a suction pump connected to the suction tube.
18. A device of the class described, comprising a casing, a hollow shaft rotatably mounted within the same, a motor, and means intermediate of said motor and the hollow shaft for driving said shaft at a lower speed than the speed at which the motor is driven, a cutting head attached to said shaft and a suction tube extending through the cutter head and through the hollow shaft, and suction-exerting means connected to the suction tube.
19. A device of the class described, comprising a casing, a motor mounted within the same, a shaft within the casing, and driven by said motor, a cutting head fixed on one end of said shaft, an opening in the lower

end of said cutting head, and a suction tube extending through said shaft and into the opening in the cutting head.

20. A device of the class described, comprising a casing, a motor mounted within the same, a shaft within the casing driven by said motor, a cutting head fixed on one end of said shaft, said cutting head being provided with a plurality of toothed, rotatably

mounted cutting members, said cutting head also having a suction opening, a suction tube extending through said shaft and entering into said suction opening and means for exerting suction through said tube.

Signed at the village of Highland, county of Ulster, State of New York, this 11th day of February, 1920.

HENRY F. BLACKWELL.
